UNITED STATES PATENT OFFICE.

JOHN STUART DANIELS AND FREDERIC LIONEL DANIELS, OF STROUD,
ENGLAND.

GAS-PRODUCER.

SPECIFICATION forming part of Letters Patent No. 738,004, dated September 1, 1903.

Application filed April 6, 1903. Serial No. 151,327. (No model.)

To all whom it may concern:

Be it known that we, JOHN STUART DANIELS and FREDERIC LIONEL DANIELS, both of Light-pill Iron Works, Stroud, in the county of Gloucester, England, have invented certain new and useful Improvements in Gas-Producers, (for which we have made application for Letters Patent in Great Britain, No. 7,613, dated March 29, 1902,) of which the following

is a specification.

This invention relates to improvements in connection with gas-producers that are for use with bituminous coal or other fuel containing volatile matters, the object being to improve the means for collecting and utilizing the distilled and condensable gases from the upper portion of the producer and to improve the method of constructing and arranging the fire-bars and other fittings for use upon such producers.

Referring to the accompanying drawings, Figure 1 is a central vertical section on line B B of Fig. 3. Fig. 2 is a similar view taken on line A A of Fig. 3. Fig. 3 is a horizontal section on line C C of Fig. 1. Fig. 4 is a central vertical section of a modified form. Fig. 4^a is a similar view at right angles to Fig. 4. Fig. 5 is a central vertical section of a still further modification, and Fig. 5^a is a section at right angles to Fig. 5.

In carrying our invention into effect in one convenient manner, as illustrated in Figs. 1 to 3, we provide a casing or inclosing shell *a*, of metal or other suitable material, within which we build up our fire-brick or other like material lining *b*. At the upper end of the casing we arrange a feeding-hopper *b'* with a valve or other covering and protecting device *b''*, and we cause the feeding-hopper tube or inner branch *f* to project below the upper end *g* of the interior chamber *e*, so as to thereby form an annular collecting head or passage, from which the distilled gases and vapors may be drawn or allowed to escape by means of an opening or openings *h'*, leading thereto.

We collect the distilled gases and other products from the upper portion of the producer by means of a branch opening *h'*, which leads

into a conduit passage or pipe *h*, that may be carried down within the material forming the lining *b* of the producer or by means of an independent exhaust pipe or pipes. The lower end of this collecting conduit or pipe *h* we join to a feeder branch *k*, which delivers the distillates and gases to the lower portion of the fire-grate within the zone of combustion. We make the delivering conduit or pipe *k*, preferably, as a central support, against which the fire-bars *l* can abut, forming such hollow central support with slots or openings, through which the distillates can be delivered and through which the steam for decomposition in the interior of the gas-producer can also pass.

We introduce steam through a nozzle *j* for the creation of an induced draft in the distillate pipe or conduit *k*, placing such nozzle in any convenient position to suit the form of conduit and connections that may be employed. We make our conduits and connections with outer flanges or doors, so that cleaning can be easily accomplished by the removal of such covers.

Within the interior of the producer we sometimes arrange our improved projecting ring-like collector *d* for leading to the gas-outlet passage. We, however, make our collector *d* in various forms to suit the size of producer that is to be constructed and the connections that are to be used with the same. We arrange our fire-grate in the form of bars *l*, which we carry on central spindles *m* or bearings that are capable of being rocked, so that the bars are made to move to a determined extent by the rocking of the spindles, and thus to break up the fuel supported thereon and to obviate the clinkering, which would otherwise result. The spindles *m* are provided with exterior hand-levers *n*. The levers are adapted to move between removable and adjustable stops, (not shown,) which limit the amount of rocking that can be given to the grate and which can be removed altogether when desired to allow the grate to be turned through a considerable angle when the producer is open for cleaning. We prefer to make the

rocking bars l to intermesh on their inner ends with projecting bars q , formed upon the bearer members k , and we make the ends s of the rocking bars of such a form that they do not move entirely away from the lower end of such fixed bars. By this provision we prevent the entrance of small pieces of clinker or coal between the fixed bars and the rocking-bars.

10 We sometimes employ supplementary or auxillary grate-bars o within our furnace-grate, and we make these auxiliary bars as fixtures or to rock, as may be desired, preferably mounting them in such a position, as 15 shown in Fig. 1, that an angular bed-like support is formed for the fuel at its base. These auxiliary bars serve to hold the fire clear of the water ash-pit p and to form an additional support for the side surface of the 20 fuel at its base. Air is supplied beneath the grate by a pipe t .

At the lower end of our gas-producer casting we provide an ash-pit p , which we fill to any desired level with water, making such 25 ash-pit preferably of greater dimensions than the exterior portion of the casing of our producer.

When constructing another form of our improved gas-producer, as illustrated in Fig. 4, 30 we arrange our rocking bars at the lower sides of a wedge-like base c of the producer-chamber e , (which chamber is of rectangular cross-section,) and we make such bars to intermesh at their ends with fixed ribs or bars q' , 35 formed upon the bearer-supports r , and similar ribs q^2 upon the sides of the open passage or ash-pit waste-outlet r' between the inclined bars. We cause these bars to rock on either side, so as to obtain a complete dis- 40 turbance of the fuel upon the bars when in operation. In this form we have omitted the annular collector d , providing simply a single collecting-outlet d' at one side. We also provide a steam-injecting pipe j' in the pipe 45 or conduit h . In this form it will be seen that the distillates are passed through conduit h into the central hollow perforated conduit k , the fire-bars being disposed on each side thereof.

50 By another modification of our improved gas-producer, as illustrated in Fig. 5, we provide for a treatment of fuel in small and medium quantities by mounting the rocking fire-bars l^2 in an inclined manner upon a shaft m^2 55 on one side of the base of the hearth, making the conduit-passage h for the distillates to enter the central bearer-like member k' , on each side of which the bars are mounted or supported, and we arrange projecting bars q^3 60 to intermesh with the openings of our rocking bars in the manner and for the purpose hereinbefore described. In this form of construction of gas-producer we deliver the air by a conduit t' to the under side of the grate, 65 through which it passes.

We provide for the ash removal by forming an open channel x at one side of the base of the grate, which channel leads to the trough or water-chamber p^2 , arranged beneath the base of the fire-grate, such chamber being 70 made of any desired form to suit the mountings and fittings in connection with the casting to which it is to be applied.

We do not limit the application of our improved arrangement of rocking bars and the 75 improved method for collecting and feeding the distillates and steam to the fire-grate to any particular form of casing or any special arrangement of water-trough or other fittings to be used in connection with such gas-producers; but we modify the arrangement and the construction of such members to suit the 80 type and size of gas-producer that is to be constructed and the fittings to be employed therewith.

Having thus described our invention, what we claim as new, and desire to secure by Letters Patent, is—

1. In a gas-producer the combination with the producer-chamber, of a hollow perforated 90 conduit having communication with the upper part of the producer and arranged to support fuel and to deliver distillates thereto, and inclined pivoted fire-bars on each side of said conduit, substantially as described.

2. In a gas-producer the combination with the producer-chamber, of a hollow perforated conduit having communication with the upper part of the producer and arranged to support fuel and to deliver distillates thereto, inclined pivoted fire-bars on each side of said conduit, and fixed bars arranged adjacent to said pivoted bars, substantially as described.

3. In a gas-producer the combination with the producer-chamber, of a centrally-located 105 hollow perforated conduit having communication with the upper part of the producer, and inclined pivoted bars on each side of said central conduit and fixed bars on the exterior of said conduit coöperating with said rocking 110 bars, substantially as described.

4. In a gas-producer the combination with the producer-chamber, of a centrally-located hollow perforated conduit having communication with the upper part of the producer, inclined pivoted fire-bars on each side of said 115 conduit with means for rocking them, auxillary side bars coöperating with said grate-bars, and means for rocking said side bars, substantially as described.

5. In a gas-producer the combination with the producer-chamber, of a centrally-located hollow perforated conduit having communication with the upper part of the producer, and rocking grate-bars inclining downwardly 125 from each side of said conduit, substantially as described.

6. In a gas-producer the combination with the producer-chamber, of a centrally-located hollow perforated conduit having communi- 130

cation with the upper part of the producer, and rocking grate-bars inclining downwardly from each side of said conduit, fixed bars on said conduit, coöperating with the adjoining edges of said rocking bars, and supplemental rocking bars coöperating with the outer edges of said grate-bars, substantially as described.

In witness whereof we have hereunto set our hands in presence of two witnesses.

JOHN STUART DANIELS.

FREDERIC LIONEL DANIELS.
